UNITED STATES PATENT OFFICE.

ANTHONY HESSELS, OF NEW YORK, N. Y.

MACHINE FOR CUTTING DIAMONDS.

SPECIFICATION forming part of Letters Patent No. 249,523, dated November 15, 1881.
Application filed September 25, 1880. (No model.)

To all whom it may concern:

Be it known that I, ANTHONY HESSELS, of the city, county, and State of New York, have invented certain new and useful Improvements in Machines for Cutting Diamonds, of which the following is a specification.

This invention relates to improvements in the machine for cutting diamonds for which Letters Patent have heretofore been granted to me, numbered 216,955 and dated July 1, 1879, so as to simplify the construction and avoid nearly entirely one objectionable feature—to wit, the cementing of the diamonds to the dops by tin-solder.

15 The cementing of the diamonds to the dops is connected with several disadvantages: first, it requires time to heat up the tin-solder on a jeweler's lamp for putting on or removing the diamonds, and, secondly, the upper cutting-diamond carries frequently small particles of the tin-solder over the surface to be cut, so as to scratch or otherwise injure the same, which frequently necessitates the recutting of the facets and considerable loss of time.

25 Heretofore it has not been believed to be possible to hold the diamonds in any other manner than by means of the tin-solder; but I have discovered by practical tests that the diamonds may also be firmly and securely held 30 in position by properly-constructed chucks, by the use of which the objections heretofore stated are fully avoided and a considerable saving of time and labor in cutting the diamonds obtained.

35 My invention consists of a series of chucks in which the diamond is securely held by adjustable jaws, sockets, and retaining-tongues.

It consists, secondly, in securing the round or octagonal shanks of the chucks into the socket of a cylinder pivoted to an axially-adjustable auxiliary frame, which latter is supported on a laterally-adjustable slide-frame of a longitudinally-reciprocating carriage. The socket-cylinder is supported on a laterally-adjustable block of the auxiliary frame and secured to the frame by a clamp-screw.

45 In the accompanying drawings, Figure 1 represents a plan view of my improved machine for cutting diamonds; Fig. 2, a front elevation, partly in section; and Figs. 3, 4, 5, 50 and 6 are top and side views, on an enlarged scale, of different chucks, adapted for holding

the diamonds during the different cutting operations. Fig. 7 is a vertical transverse section through the lower slide frame and the parts connected by it. Figs. 8 and 9 are, respectively, a top view and a vertical transverse section on line *x x*, Fig. 8, of the upper slide-frame and pivot-socket. Figs. 10 and 11 are vertical transverse sections of the chucks, shown respectively in Figs. 4 and 5, and Fig. 6. 612 is a detail view of a slotted retaining-arm or holder of the chuck.

Similar letters of reference indicate corresponding parts.

In the drawings, A represents the horizontally-reciprocating frame of the upper cutting-diamond, which frame is guided in a vertical standard, A', and set in motion by a crank-connection with the driving-shaft. The top frame, A, carries a vertically-adjustable frame, B, to which a socket, B', is pivoted, into which, instead of the dop heretofore employed, a chuck, C, that carries the cutting-diamond is firmly secured by a set-screw. The vertically-adjustable frame B is provided with a ratchet-and-pawl feeding mechanism, as shown in Figs. 1 and 2, by which the cutting-diamond is gradually fed downward, so as to abrade the facets on the diamond. The lower diamond is, in similar manner as the rough-cutting diamond, held by a chuck, D, which is set into a socket, E—that is, pivoted to supports of an axially-adjustable auxiliary frame, E'. The auxiliary frame E' is guided by arc-shaped slots *a*, along fixed screw-posts *b* of a laterally-adjustable slide-frame, F, which is guided on rails of the longitudinally guided and reciprocated carriage F', the latter receiving, like the horizontal frame of the cutting-diamond, its motion from the driving crank-shaft, as shown in Fig. 1.

65 By the pivot-connection with the auxiliary frame E' the socket E may be set to any angle toward a perpendicular line, as required by the facets to be cut. The socket E may also 70 be turned by the auxiliary frame around the vertical axis of the latter for the purpose of bringing the grain of the stone into proper direction toward the cutting-diamond.

75 The pivoted socket E rests upon an adjustable block or cheek-piece, E'', which may be moved forward or backward in guide-grooves

of the auxiliary frame E' by means of an adjusting-screw, d, which engages the block E², and is retained in a fixed guard or bail, d', of the auxiliary frame by means of shoulders or 5 collars d².

The diamond supported in the lower chuck, D, may be readily adjusted into any desired position or angle toward the cutting-diamond, so as to cut any front or back facet of the same 10 with absolute accuracy and certainty, whatever be the grain of the stone.

The chucks C and D are constructed with round, octagonal, or other shanks, which are set into correspondingly-shaped holes of the 15 sockets and secured therein by means of set-screws. In my former patent referred to a cylindrical dop-socket was turned, together with the dop and stone, while now I turn the stone in the chuck without changing the position of 20 the chuck in the socket.

For cutting the different facets of the diamonds the construction of the chucks has to be modified. The table and cullet of the diamond I prefer to cut in the old manner by soldering the rough diamond into its dop, but the 25 front and back facets I cut by means of diamonds which are set into chucks of different constructions, as shown in Figs. 3, 4, 5, and 6.

Each chuck is provided with a transverse 30 center piece, e, of dovetail shape, which is set into a transverse center recess of the chuck and secured by a screw, e'. The center pieces, e, are made of different thicknesses and are interchanged according to the size of the stone 35 to be cut. The chuck C of the upper cutting-diamond is provided with a retaining-tongue, f, which is adjusted by a slotted-arm, f', extending at right angles therefrom and being attached by a clamp-screw, f², to one side of the 40 chuck C, and by a clamp-screw, f³, to the top of the same, as shown clearly in Figs. 2 and 6.

The center piece, e, has a tapering socket for receiving the back portion of the diamond. For cutting the front facets, center pieces, e, 45 with sockets of different sizes are also employed in the chucks, while for the back facets the chuck D, shown in Figs. 3 and 4, is used. The chuck, shown in Fig. 5, is employed for shaping the front of the stone by cutting the main 50 front facets. The chuck D is also provided with guided and laterally-adjustable side jaws, g, which are set to the diamond by screws g', turning by retaining-collars in end flanges of the chuck. The jaws g have inclined edges 55 which bear on the stone and hold the same firmly in position on the interchangeable cen-

ter piece, as shown in Fig. 4. A transverse stop, g², with threaded shank, turns in a center lug of the chuck and serves as a rest for the diamond, preventing any change of position 60 transversely to the jaws. In the chuck shown in Fig. 5 the jaws are furthermore provided with inclined rectangular recesses at the edges. By means of these chucks the diamond to be cut may be exposed to the action of the upper 65 cutting-diamond in any desired position, so as to cut any one of its facets, the back facets being first cut and finally the front facets. By the adjustability of the chuck-sockets the proper angle of inclination for the facets and the 70 proper direction of their grain toward the cutting-diamond is obtained, while by the chucks the setting of the diamond so as to cut one facet after the other is accomplished quickly and without the tedious soldering of the same 75 into the old-style dops.

Having thus described my invention, I claim as new and desire to secure by Letters Patent—

1. In a diamond-cutting machine, the upper cutting-diamond holders, consisting of the longitudinally guided and reciprocating carriage, the vertically-adjustable slide-frame, an axially-adjustable frame, and a socket pivoted and secured thereto, in combination with the lower diamond-holders, consisting of an axially-adjustable auxiliary frame, E', having a chuck-socket, E, pivoted thereto, and a cheek-piece, E², adjustable, as set forth, to support the socket, substantially as specified. 85

2. In a machine for cutting diamonds, a chuck provided with rectilinear laterally-adjustable jaws which have beveled ends, in combination with the interchangeable transverse center-piece and the chuck-plate D, substantially as described. 90

3. In a machine for cutting diamonds, a chuck provided with laterally-adjustable retaining-jaws, interchangeable center-piece, and a transverse stop, substantially as described. 95

4. The upper cutting-diamond-holding chuck, composed of the bifurcated and adjustable retaining-tongue, in combination with the transverse interchangeable center-piece and the chuck-plate, substantially as described. 100

In testimony that I claim the foregoing as 105 my invention I have signed my name, in presence of two witnesses, this 16th day of September, 1880.

ANTHONY HESSELS.
